UNITED STATES PATENT OFFICE.

ODILON BRISBOIS, OF CHICAGO, ILLINOIS, ASSIGNOR TO JOHN H. WARE, OF CHICAGO, ILLINOIS.

PREPAY-BOX FOR USE IN TELEPHONE SYSTEMS.

1,160,570.

Specification of Letters Patent. Patented Nov. 16, 1915.

Application filed February 8, 1915. Serial No. 6,837.

To all whom it may concern:

Be it known that I, ODILON BRISBOIS, a citizen of the United States, and a resident of Chicago, in the county of Cook and State 5 of Illinois, have invented certain new and useful Improvements in Prepay-Boxes for Use in Telephone Systems, of which the following is a specification.

This invention relates to a toll box suitable for use in a two wire telephone system of that class in which a prepay or pre-payment is required before a signal can be given by the party desiring to use the telephone.

The invention has particular reference to 15 a party line system, and the construction herein illustrated and described, and which embodies the invention, is well adapted for use in what is known as the automatic type of telephone systems; that is, those systems 20 wherein selective mechanism at a central station is substituted for skilled operators, as the means of establishing the circuit desired. In systems of this character the selective mechanism referred to is operated by im- 25 pulses of current which are delivered by mechanisms which may be and usually are mounted in the bases of the several telephone instruments which are installed in the system. And in these systems a plurality 30 of telephone instruments are installed on a given circuit from the central station, and any one of said instruments may use the line as a calling or called station. The instruments which are included in these stations 35 which are adapted to call or to be called comprise, usually, the telephone, the ringing box, the coin box, and the adjacent and interrelated connections.

The object of this invention is to obtain 40 a device of the kind named, by means of which when a circuit has been established by any one of the several party stations on a given circuit the same cannot be interrupted or broken by a party at any of the 45 remaining stations on said circuit; to obtain a device by means of which a party at a given station who is attempting to establish a circuit which shall include a desired station, will be advised whether the side of 50 said circuit which comprises said given station is or is not already in use; to obtain a device by means of which a party desiring to establish a circuit which will include as elements thereof the telephone transmitters 55 and receivers of the calling and the called

stations, will retain control of the final disposition of the coin which is required to be inserted in the slot or runway, provided therefor, until said party at said calling station is made aware that said called station 60 is not in use otherwise and has responded to said call; and a device by means of which, upon the failure of said called station to respond to said call, said calling party is advised of said failure, and the coin which 65 has been inserted, as aforesaid, may be regained.

Additional and important objects sought by me are to obtain such interdependence between the operation of the signaling and 70 selector mechanisms, the listening and talking mechanisms, and the coin box mechanism as to make it imperative that a calling party place a coin in the runway or slot provided therefor before he can obtain oper- 75 ative actuation of his selector mechanism to signal or call a party; and to obtain such interrelation and interconnection between the different instruments of the stations which are installed in the system as to make 80 it necessary for said calling party to deposit said coin so contained in said slot or runway, in a receptacle provided therefor, and be- 85 yond his control, before a conversation with said called party can be carried on; hence, 90 the mechanism embodying means to effect the last above recited objects require the calling party to insert a coin in the slot or runway of the device before he can make a call, and on being advised that his call is 95 responded to, to deposit said coin beyond his control before he can converse with said called party, while if the call is not responded to he can regain said coin.

In the drawings accompanying and form- 95 ing a part of this specification Figure 1 shows a vertical section of a device embodying the invention, on line 1—1 of Fig. 2, viewed in the direction indicated by the arrows. Fig. 2 shows a vertical section on 100 line 2—2 of Fig. 1, viewed in the direction indicated by the arrows. Fig. 3 represents a vertical section on line 3—3 of Fig. 2, viewed in the direction indicated by the arrows, the parts shown being viewed at 105 an angle of 180 degrees from the view shown in Fig. 1. Fig. 4 shows a horizontal section on line 4—4 of Fig. 3, viewed in the direction indicated by the arrows. Fig. 5 shows in detail the float arm of the device, 110

and the contact leaves thereon, said leaves standing in their normal position. Fig. 6 shows a view similar to Fig. 5, of the parts illustrated in said Fig. 5, with the contact leaves forced down by a coin resting on the float arm. Fig. 7 is a bottom plan view of the selective mechanism in a telephone stand, which is adapted to be used in a telephone system which is equipped with devices embodying this invention. Fig. 8 is a vertical section on line 8—8 of Fig. 7, viewed in the direction indicated by the arrows. Fig. 9 is a detail of the terminals of the selective mechanism which is illustrated in Fig. 7. Fig. 10 is a diagram of the condition of the circuits of the device, when installed on a party line, the receiver being on the hook of the stand which is provided therefor, and the device being in a usable condition, showing in elevation a coin partially inserted in the slot of the device. Fig. 11 is an elevation of a lock lever and latch thereto, in position not permitting the insertion of a coin in the coin slot. Fig. 12 is a diagram illustrating a circuit in which the selective mechanism of the telephone instrument is an element, the receiver being off its hook and a coin on the float bar of the device. Fig. 13 is a diagram illustrating a circuit which is established when said receiver is off the hook therefor, a coin is on said float arm, and the push button of the device is depressed. Fig. 14 is a diagram illustrating a circuit which is established when said receiver is off said hook, said coin has been discharged from said float arm, and the push button has been returned to its normal and initial position. Fig. 15 is a side elevation of the contact points which are controlled by the receiver and hook therefor, showing said contact points in position with the receiver on its hook. In Fig. 14 the contact points which are illustrated in Fig. 15 are shown in position with the receiver off the hook therefor; and what I term the talking circuit is established. To break said circuit and establish what I term the normal circuit of the device it is simply necessary to return said receiver to said hook, thus bringing said contact points into electrical connection.

In the construction which is illustrated in Figs. 1 to 7, both inclusive, placing a coin in the coin slot and on the floating bar of the device places the calling party in circuit with the central selective mechanisms, and upon operation of the selective mechanism in the telephone instrument by the calling party the called station is in the circuit which is established; and in case the called party is not obtained, either by his failure to raise the receiver off the hook therefor in the called station, or by reason of the mechanism failing to operate properly, the original coin can be regained, by

means hereinafter set forth, and an additional attempt to obtain said station may be made.

To advise the party calling that the desired circuit has been established, and that a party at said called station has raised the telephone receiver off from the hook thereof; that is, the call is responded to; means are provided whereby, a coin being on the float arm, and the receiver at the calling station being off the hook, the receiver and transmitter of said calling station are bridged directly across the line; and, to prevent conversation being carried on while permitting the response to be heard by the calling party, sufficient resistance is interposed in said bridging circuit to force some of the current generated by said response through the receiving circuit of the calling station; hence the calling party can imperfectly hear a response given to him by the called party. It becomes necessary, therefore, for the calling party to break said bridge, by removing said coin from said floating arm, and means are provided so that the coin removed under or at the time of the last above recited conditions will be deposited in the safe of the device.

In the constructions which are illustrated in the drawings there is a casing, comprising a base and a shell or cover, said shell being provided with a coin slot for receiving a coin and an additional slot for discharging said coin from said casing, when desired, a tray to receive a coin discharged from said last named slot, a locking bar to control the admission of a coin to said first named slot, a latch to said locking bar, an electro-magnet to control the position of said latch, a resistance coil, and a circuit in which said resistance coil and the coils of said electro-magnet are elements, a runway from said receiving slot, a float arm, or float bar, adapted to receive a coin discharged from said runway, additional runways respectively adapted to receive a coin discharged from said float arm, a safe, one of said last named runways adapted to discharge into said tray and the other into said safe, an electromagnet adapted to control said float arm, and a circuit in which the coils of said electromagnet are elements, with additional circuits hereinafter set forth. There is such interconnection and inter-relation between the several elements entering into the construction of the device embodying this invention and the selecting mechanism, the standard, receiver hook post, the receiver and transmitter, and what may be termed the signaling and talking circuits of the automatic telephone instrument to which this device is attached as is required to obtain the results sought, and so much of the construction of said telephone instrument as is required to understand this device and its

relation to the telephone instrument is hereinafter set forth.

A reference character applied to designate a given part indicates said part throughout the several figures of the drawings, wherever the same appears.

1 designates the base of a coin box; 2 the shell or cover thereof; 3 a slot adapted to receive a coin; and 4 a runway. 5 indicates a float arm, or float bar; 6 and 7, respectively, indicate runways; 8 a tray; 8^a a slot adapted to discharge into said tray; and 9 a safe, or coin receptacle.

10 designates a lever which is hereinafter referred to, in connection with a latch (12), as a lock; and 11 a screw which serves as the pivot on which lever 10 turns, and also as the means whereby the plates or sheets of metal in which the several runways are 20 pressed, are held together in proper relative position.

11^a is a leaf contact point, and 12^a is a stationary contact point adapted to co-act with said leaf contact point. Latch 12 is mounted 25 on the spring 13, underneath the free, or movable, end of lever 10, when in its normal position, to prevent its depression. Latch 12 is shown made of soft iron and forming the armature of electromagnet 14.

15 and 16 are electromagnets, and 17 is the armature of said magnets. The float arm, or float bar 5 is attached to armature 17.

18 is a resistance coil.

19 is a push button.

20 In the several drawings 20 represents a conductor from an exchange, which is indicated by the numeral 22, and 21 represents an additional conductor from said exchange.

23, 24, 25, and 26 represent line conductors from conductors 20, 21, to subscribing party stations.

27 and 28 are the two wires or conductors of line 26, and lead to the station wherein a toll box embodying this invention is installed. The call or ringing box of said station embodying this invention is designated 29; and it is provided with the usual ringing coils 30, 31, and condenser 32.

33, 34, designate terminals to the ringing coils 30, 31, respectively; and 35 designates the terminal to condenser 32.

36 designates the base of the telephone instrument, 37 the transmitter and 38 the receiver. The hook on which the receiver normally hangs, or rests, is not illustrated, as it is operated in the usual manner, by placing the receiver thereon and removing it therefrom, and of course forms, of itself, no new feature in the device. The hanging of the receiver on its hook and removing it therefrom performs the usual operation of raising and lowering a post or rod, and said post or rod is designated by the numeral 39. The raising and lowering rod or post 39 raises and lowers the leaf contact 40.

In Fig. 8 the post is shown depressed, that is, with the receiver off of its hook, and said leaf contact is shown in contact with contact 42. When the receiver is placed on its hook said leaf contact 40 is raised and comes 70 in contact with contact 41. 43, 44, 45 and 46 are the contact points of a signal mechanism such as is ordinarily used on an automatic telephone points 43 and 44 being normally in contact and the operation of which 75 is not required to be herein described; other than to suggest that means are provided whereby when the signaling mechanism is operated, in the usual way, the points 45 and 46 are brought together and are so held 80 while points 43 and 44 are separated and brought together and each time the points 43 and 44 come together an impulse of current must be delivered to the line, over a circuit hereinafter described. Spring contacts 45 and 46 thus perform their function, which is to close the circuit comprising, (see Fig. 12), terminal 59, conductors 67, 68, 70, contact points 45, 46, conductor 72 and terminal 64, and shunt the telephone instruments on the circuit which comprises said terminals, the conductor 57, transmitter 37, conductor 58, terminal 60, conductor 64, terminal 63, conductor 61, receiver 38, conductor 62; and the said closing of contacts 45, 46, constitute the succession of makes and breaks which are being made in series circuit over the two sides of the line during the selecting operations which, (under the control of the calling subscriber), operate at the central station to complete the connection. 47 is a leaf contact point which is raised and depressed by the raising and depressing of the push button 19. 48 is a contact point with 95 which contact point 47 is normally in electric contact; that is, when push button 19 is not in a depressed position. 48^a is a contact point with which said leaf contact point 47 is in electrical contact when said contact 100 point 47 is depressed, by depressing the push button.

Before designating and describing the several connecting wires, or leads, in and about the toll box embodying this invention I will give, in a brief form, the different circuits which are established in the operation of the device.

1. A ringing circuit which is indicated on Fig. 10 by an arrow lettered "R". This 120 circuit is established by hanging the receiver on its hook when use of the telephone is discontinued. When this circuit is energized at a called station a signal is given.

2. A talking circuit which is indicated on 125 Figs. 12 and 14 by an arrow lettered "T". This circuit is established by taking the receiver off its hook. In non-pay stations this circuit is used, immediately it is established, to send operating pulsations from a calling 130

station to the selective mechanism at the central station of the system; and (either from non-pay stations or from stations where this device is installed) this is the circuit over which, (after connection between a calling and a called station has been made), conversation is carried on. At stations where this device is installed operation of the selective mechanism at the central station of the system is not obtainable over this circuit until a deposit of a coin on the float bar (5) is made.

3. An interlocking or interconnecting circuit which is indicated in Figs. 10 and 14 by an arrow lettered "I". This circuit is established at all times when no coin is on the float bar 5; and is adapted to be energized on the establishment of the "T" circuit, with which it is interconnected. It shunts the signaling mechanism of the calling station and interferes with the operation of the signaling mechanism. This circuit is broken by the weight of a coin on the float bar 5, and when it is broken operating pulsations may be sent from said selecting mechanism of the calling station to the selective mechanism of the central station.

4. An unlocking circuit, which is indicated by an arrow lettered "U" in Fig. 10. This circuit is established and energized by attempting to put a coin in slot 3 of the toll box. When the device is installed at a station in a party line system and the line is not in use, the establishment and energizing of this circuit unlocks the slot (3) and a coin can be inserted. If the party line is in use by other subscribers at the time an attempt is made to insert a coin in said slot the circuit will be established, but will not be sufficiently energized to operate the unlocking mechanism of the slot, and said coin cannot be inserted therein.

5. A signaling circuit which is indicated by the arrows lettered "S" in Fig. 12. This circuit is established by the establishment of the "T" and the breaking of the "I" circuits. When this circuit is established the selecting mechanism at the calling station is adapted to send operating pulsations to the selective mechanism at the central station, and the calling party, by operating said selecting mechanism, will obtain connection with the called station, and a signal will be given at said called station.

55. 6. A listening circuit which is indicated by the arrows lettered "L" in Fig. 12. This circuit is established at the same time and by the same means as the "S" circuit is established; but is not usable until the selective mechanism at the central station has been operated, a connection has been made with a called station and the receiver at said called station has been taken off its hook. By means of this circuit a response from

65 the called station is audible, but conversa-

tion cannot be carried on until the "B" circuit, which is about to be described, is broken.

7. A bridge circuit which is indicated by an arrow lettered "B" in Fig. 12. This circuit is established by the establishment of the "S" and the breaking of the "I" circuits. It bridges the telephone receiver and transmitter, and is broken by the discharge of a coin from float bar 5, on depression of the push button 19.

8. A final circuit which is indicated by arrows lettered "F" in Fig. 13. This circuit is established to effect the discharge of a coin from the float bar. When the "F" circuit is closed the resistance of coils 15 and 16, (which are elements of this circuit), is so high that the current on the line is not sufficient to actuate the selective mechanism at the central station, and hence, if the receiver at the called station has not been removed from its hook before the establishment of said "F" circuit, the connection will be discontinued; on the other hand, if said receiver has been removed from its hook the establishment of this circuit will not break or discontinue said connection. When this circuit is established and the connection with the called station is discontinued, the circuit is locally energized, and thereby float arm, or bar, 5, is moved to discharge the coin on said float bar into runway 6, through which it moves to tray 8^a. When said connection with said called station is not disconnected, (the receiver at said called station being off its hook) said circuit is energized from said called station, and thereby float arm 5 is moved to discharge said coin from said float arm to runway 7, through which it moves to safe 9.

Referring again to the several connections or leads on the drawings, incoming wire 27 is connected to leaf contact point 47. 49 is a lead from contact point 48 to terminal 33. 50 is a post in the base of the telephone instrument, and 51 is a lead from post 50 to terminal 33. The outgoing wire 28 is connected by the lead 51^a to post 52, in the base of the instrument. Condenser terminal 35 is connected by lead 53 to post 54 in the base of the instrument. The posts 50 and 52 are generally designated as the "line posts"; and they are the posts whereby communication is established between the telephone and the line during ordinary service. In this device the incoming wire extends to the leaf contact 47, thence through contact 48 and on lead 49 to terminal 33; thence on lead 51 to said post 50; and the outgoing wire extends from terminal 34 on lead 51^a to post 52. A lead 55 connects the post 50 to leaf contact 40, and a lead 56 connects the stationary contact point 41 with the ringing post 54.

From the foregoing it will be seen that as

long as the receiver remains on its hook, and the push button (19) is in its normal condition, a connection is established between the posts 50 and 54, thereby placing the ringing box directly across the lines 27 and 28, forming what I have termed the "R" circuit. When thus connected the ringing box is ready to receive any ringing currents which may be delivered over the lines from the 10 exchange.

The transmitter is connected by the leads 57 and 58 with a pair of "transmitter posts", 59 and 60, in the base of the instrument, and the receiver is connected by a pair of leads 15 61 and 62, with the pair of "receiver posts" 63 and 64, in said base. A permanent connection, 65, is placed between the posts 60 and 63, so that said posts always are in electric connection.

20 The lead 66 connects the leaf contact 42 with the post 64, and when the receiver is off its hook, as in Fig. 12, direct connection is established with one side of the receiver. Thence the circuit extends through the connection 65 to the transmitter, thus placing 25 the receiver and transmitter in series. A lead 67 connects the post 59 to the contact points 43 and 45 of the signaling mechanism, through the medium of the leads 68, 30 69 and 70, and a lead, 71, places the contact point 44 in connection with the post 52, so that as long as the points 43 and 44 remain 35 in contact communication is established between the transmitter post 59 and the outgoing line post 52.

From the foregoing it will be seen that as soon as the telephone receiver is raised from its hook the ringing circuit is broken by reason of the forcing of the leaf contact 40 40 away from the contact point 41; but that immediately the transmitter and receiver are bridged across the line by the closing of the contact points between the leaves 40 and 42. Under these circumstances a conversation may be carried on, in the usual 45 manner, with any called station which has been placed on an established circuit, so soon as the receiver at said called station has been taken off its hook. This circuit is indicated in Fig. 12 by the arrow marked "T", and consists of the elements 27, 47, 48, 49, 33, 51, 50, 55, 40, 42, 66, 64, 62, 38 (the receiver), 61, 63, 65, 60, 58, 37 (the transmitter) 57, 59, 67, 68, 69, 43, 44, 71, 52, 51^a, 55 34 and 28.

To signal the central exchange, so as to operate the selective mechanism there, the contacts 45 and 46 are to be brought together the desired number of times to give 60 the desired number of impulses or pulsations of current on the line for operating the selective mechanism. This signaling current is sent directly to the exchange, (not through the telephone transmitter and receiver of the calling station), and for this

purpose the receiver post 64 is connected by lead 72 to contact point 46, so that said contact point will be brought to potential equal to that of the incoming line 27 the instant the telephone receiver is raised from its hook. So soon as the receiver has been raised, so as to energize the contact point 46 the signal mechanism may be operated. This will bring the points 45 and 46 together, and each time the points 43 and 44 75 come together an impulse of current will be delivered to the line. Such impulse will be delivered over the circuit which is indicated by the arrow lettered "S", and comprises the elements 27, 47, 48, 49, 33, 51, 50, 55, 40, 42, 66, 64, 72, 46, 45, 70, 69, 43, 44, 71, 52, 51^a, 34 and 28.

As the effective working of the "S" circuit obviates the necessity of placing a coin in slot 3 and on float bar 5, I provide means 85 for breaking said circuit, or for preventing its proper function, to prevent the selective mechanism at the exchange from being operated by the operation of the signal mechanism at the calling station; and this is circuit "I", which is based on the principle 90 that the selective mechanism of the exchange will only operate through the medium of pulsations of current properly delivered from the calling station. The means 95 which I employ in the construction illustrated comprises contact points 82 and 83 on float arm 5, leads 89 and 90, terminals 84 and 85, leads 94 and 95, and the contact points 43, 44 and 45. To understand the 100 manner in which this "I" circuit is broken the construction of the float bar, or float arm, 5 will be here explained, and its operation.

Float bar 5 is pivoted in the usual manner, 105 at 74, and adapted, when in its neutral position, to retain a coin thereon; and arranged to swing to and from said neutral position. The direction in which said float bar swings is controlled by the direction 110 of the current through the coils of electromagnets 15 and 16, to deliver a coin thereon into runway 6 or 7. When said coils are energized by a local current said coin is delivered into runway 6 and tray 8; and 115 when energized by a current from the called station said coin is delivered into runway 7 and safe 9. If the receiver at the called station is on its hook at the time of the establishment of the "F" circuit said coin is 120 delivered to runway 6, and if said receiver is off its hook at said time it is delivered to runway 7. Said float arm carries the upper contact leaf 75, and the lower contact leaf 76, and these leaves normally stand in the 125 position in which they are illustrated in Fig. 5.

77 and 78 are insulating blocks interposed between the respective leaves 75 and 76 and said float arm 5. Insulating plug 79 joins 130

the leaves 75 and 76 mechanically together, although they are electrically separated, and leaf 75 projects into the path of a coin on said arm 5. Leaf 75 also carries the contact point 80, which is adapted to come in contact with the electric point 81, and does so come in contact when a coin is on said leaf. Point 81 is electrically insulated from arm 5.

10 82 is a contact point which is carried by leaf 76, and 83 is an electric point which is mounted on said arm 5, but electrically insulated therefrom. 84, 85, 86, 87 and 88 are terminals of the coin box. Leaf 76 is an electric conductor, and terminal 82 is electrically connected to terminal 84 through the medium of said leaf and lead 89. Contact point 83 is electrically connected to terminal 85, by means of lead 90. The leaf 15 contact point 80 connects to the terminal 86 by means of lead 91, resistance coil 18, and lead 92. The contact point 81 connects to the terminal 87 by means of lead 93. Terminal 84 connects to contact point 44 by means of lead 94, and terminal 85 connects to contact point 43 by means of lead 95. Terminal 86 connects to the receiver post 64 by means of lead 96, and the terminal 87 connects to the transmitter post 59 by means 20 of lead 97. Post 59 is connected to contact 43 by leads 67 and 69 and post 52 is connected to contact 44 by means of lead 71. Said contacts 43 and 44 are connected also by means of leads 94, 95, terminals 84, 85, 25 leads 89, 90, and contacts 82, 83.

It will be seen that contacts 43, and 44 of the signal mechanism, being directly connected to post 59, so long as the points 82 and 83 remain closed, any opening or closing, (or making and breaking) the contact points 43 and 44, will be ineffectual to open or close the signal circuit, said signal circuit being shunted, as hereinbefore set out, (in the recital concerning the "T" circuit), as far 40 as the production of pulsations of current is concerned. Therefore, until said "T" (or shunt circuit) is broken it will be ineffectual to make and break the contacts 43 and 44.

If it be assumed that a coin is dropped 50 into the slot 3 and is deposited on the leaf 75 of the arm 5, the contact point 82 on said leaf 76 is thereby forced away from contact 83, by reason of the downward movement of said leaf 76 being transmitted to said leaf 76 by means of plug 79. The circuit "T" is thereupon broken and the signaling mechanism is permitted to properly function, for the pulsations of current necessary to operate the selective mechanism in the central 55 station or exchange.

To prevent a party from carrying on a conversation while the coin is on the float arm 5, I provide interlocking mechanisms (circuit "B," Fig. 12), whereby, as long as 60 said coin is on said arm the talking circuit,

that is circuit "T" is interfered with or interrupted. This circuit "B" comprises the following elements, 64, 96, 86, 92, 18, 91, 75, 80, 81, 93, 87, 97 and 59, and is a bridging or shunting circuit having its terminals at said receiver post 64 and transmitter post 59. Direct connection is thus established between said receiver post 64 and said transmitter post 59, shunting both the transmitter and receiver and their operation. While 75 this "B" circuit is closed and preventing conversation being carried on, nevertheless what I term the listening (or "L") circuit is established, and through this circuit a party at the calling station may hear sufficiently 80 well to determine whether or not a response is made at the called station. This "L" circuit comprises the elements 27, 47, 48, 49, 33, 51, 50, 55, 40, 42, 66, 64, 62, 38, 61, 63, 65, 60, 58, 37, 57, 59, 67, 68, 69, 43, 44, 71, 52, 51^a, 85 34 and 28, bridged by the "B" circuit.

To carry on a conversation it is necessary to cut out the bridge, "B", circuit, and this is effected by closing the "F" circuit, through the means of the push button 19. 90 In Fig. 13 this "F" circuit is shown as established, the push button 19 being depressed, and it comprises the elements 27, 47, 48^a, 98, the coils of the electromagnets 15 and 16, 100, 86, 101, 52, 51^a, 34 and 28. As soon as 95 this "F" circuit is closed it becomes energized, and connection with the called station having been established, with the receiver off its hook at said called station, a conversation can be carried on thereover.

The "U" circuit, which has been frequently referred to comprises the lead 102 which is connected to contact point 12^a and lead 101, lead 101 to post 50; also post 50, lead 55 to 103, lead 103 to the coil of electromagnet 14, and lead 104 from said coil to leaf contact 11^a. This circuit is closed by an attempt to insert a coin in slot 3, which attempt brings leaf contact 11^a into electrical connection with stationary contact 12^a. 110 When the "T" circuit is closed the closing of this "U" circuit bridges said "T" circuit; and the resistance of the coil of electromagnet 14 is sufficient to prevent an operating current through said coil, and its armature (12) is not drawn or moved out from under the lever 11; and hence the slot remains locked and the coin cannot be inserted therein. The coin is designated by the numerals 115 105.

106, (Figs. 3 and 4) are springs adapted to hold float arm 5 in a neutral position; but permitting its swing when the electromagnetic coils of said magnets 15 and 16 are energized. These coils are known in the art 120 as polarized relays.

I attach lead 96, of the "B" circuit to terminal post 60 or 63, instead of attaching it to post 64, at times. When said lead 96 is attached to terminal 60 or 63 the trans-

mitter alone is bridged by said "B" circuit; and in such case the response from a called station is clearly heard in the receiver 38; but when said lead is so attached conversation can be carried on by the calling station using the receiver both as receiver and transmitter; hence I deem it preferable, for general use, to attach said lead to post 64, thereby bridging both the receiver and transmitt-

10 er, as the response can be sufficiently heard at the calling station to enable the calling party to know that he has obtained the station called for and that the receiver has been taken off its hook, at said called station.

15 Electromagnets 15, 16, are of the kind known as a polarized relay, that is, one which, when energized with current in one direction will tend to throw its armature, (and the float arm which is attached thereto 20 and moved thereby) in one direction, while if it is energized with a current in the other direction will tend to throw said armature in the other direction.

A brief description of the operation of the 25 device is:—Assuming a calling party desires to obtain connection with another party, (called the "called party,") and the telephone of said called party is off its hook, (the R circuit at the called station being thereby 30 broken); the calling party will first remove his receiver from its hook, and he should at once attempt to deposit a coin in slot 3. In case the calling party be on a party line and the T circuit on said line is already established, the U circuit which is established by the removal of his receiver, as above, will be shunted by said T circuit so that sufficient current will not flow thereover and through the coil 14, (which is an element of 35 the U circuit), to energize it and unlock lever 10; and said deposit cannot be made. The party at the calling station will obviously hang up his receiver. In case, however, the calling party attempts to get the 40 called party without the deposit of a coin in the slot, (whether the receiver at the called station be on or off its hook), the S and I circuits are established by the act of removing the receiver at the calling station from 45 its hook, and as hereinbefore explained, no signals which will operate the selective mechanism at the central station can be transmitted over the S circuit. Assuming, however, that a T circuit has not already been established on 50 the party line of the calling station, and the coin is deposited in the slot 3, but with the R circuit broken by the receiver at the called station being removed from its hook, connection cannot be established on the called station, and ultimately the calling party will 55 return his receiver to its hook; and it is immaterial whether said return is done before or after said calling party depresses push button 19. Upon becoming convinced that 60 the connection with the called station cannot

be made, (and before or after replacing the receiver on its hook), the calling party will depress the button 19, and thereby establish the F circuit, which will be energized by a local current, and the coin which has been 70 deposited by him will be discharged into runway 6, from the float bar, and returned to him in tray 8.

Assuming the receiver at the called station to be on its hook, (with the normal and 75 established condition of circuit R existing), at the time the receiver at the calling station is removed from its hook, there will thereby be established at the calling station circuits S and I, (see Fig. 14), and any signals which 80 the calling party sends to the central station, will be so interfered with and shunted by said circuit I that the selective mechanism at said central station will not be operated so long as said I circuit is unbroken. Further 85 assuming that a T circuit is not in existence on the party line of the calling station and that the calling party deposits a coin in slot 3, before hanging up his receiver, said I circuit is thereby broken at contact points 82, 90 83, (said contact points being separated by the weight of said coin) and the selecting mechanism being operated, the makes and breaks of contact points 43 and 44, will operate the selective mechanism at said central 95 station and make connection with the called station on circuit S. In the mean time, that is, while the selecting mechanism is being operated, the telephone instruments are placed on a closed local circuit, by closing or 100 bringing together contacts 45 and 46; said local circuit comprising, (see Fig. 12) conductors 70, 67, to terminal 59, and conductor 72 to terminal 64.

On the establishment of the S circuit, as 105 last above described, the party at the called station may, or may not respond by removing his receiver from its hook. If said called party does not respond the calling party will ultimately depress the button 19, 110 and the coin will be discharged from the float arm to passage way 6 and tray 8; and it is immaterial whether the receiver be returned to its hook before or after the depression of said button. If said called party removes the receiver at the called station from 115 its hook, thereby making a talking circuit at the called station, and responds further to the call by speaking into the transmitter, the calling party can hear said response, but as the T circuit at the calling station is bridged by the B circuit, (of which resistance coil 18 is an element), so long as a coin remains on the float arm, conversation cannot be carried on; and thereupon, before a conversation can 120 be had, the calling party must depress the button 19, to discharge the coin from the float bar and permit contact points 80 and 81 to separate and break said B circuit. The T circuit remains established and is free for 125 130

conversation. On the establishment of the F circuit, by the depressing of button 19, under the conditions last above set forth, said circuit is energized by a reverse current, 5 on account of the translating operations caused by the removal of the receiver at the called station from its hook, and the armature is moved to discharge the coin on the float arm into runway 7 and safe 9.

10 I claim;

1. In a telephone prepay box, the combination of a float arm, means to hold said float arm in a neutral position, and said float arm pivoted to swing about a vertical axis, 15 a polarized relay, an armature for said relay, a connection between said armature and said float arm whereby the float arm is deflected according to the movements of the armature, a plurality of movable contacts mounted on 20 said arm, a coin seat on one of said movable contacts, and a mechanical connection between said movable contacts whereby they are forced to move in unison with respect to each other.
- 25 2. In a telephone prepay box, the combination of a polarized relay, a float arm, a vertical pivotal mounting for said float arm, an armature for the relay, a driving connection between the float arm and the armature, 30 a leaf contact above the float arm, a coin seat on said leaf contact, adapted to be deflected by a coin on said seat, a leaf contact below said float arm, stationary contacts on said arm, means to insulate said contacts 35 from said arm, and a mechanical connection between the upper and lower leaf contacts whereby said leaf contacts move in unison when deflected by a coin on said seat, to alternately come into electrical contact with 40 the corresponding ones of said additional contacts.

3. In a telephone prepay box, provided with a coin slot, means to prevent a coin from entering said slot, said means comprising a lever having its movable end in the 45 path of movement of a coin entering said slot and a latch to said lever, in combination with a movable contact, a driving connection between said lever and said contact, and a stationary contact adapted to co-act 50 with said movable contact, leads from said contacts to the line posts of a telephone instrument, an electro magnetic coil in one of said leads, an armature to said coil, and a driving connection between said armature 55 and said latch.

4. In a telephone prepay box, provided with a coin slot, means to prevent a coin from entering said slot, said means comprising a lever having its movable end in the 60 path of movement of a coin entering said slot, a latch to said lever, a movable contact, a driving connection between said lever and said contact, and a stationary contact adapted to co-act with said movable contact, line 65 posts, leads from said contacts to said posts, an electro magnetic coil provided with a core in one of said leads, an armature to said core and a driving connection between said armature and said latch, in combination with a 70 telephone transmitter and receiver, and means to put said transmitter and receiver in electric connection with said posts, the relative resistance of said recited connections between said posts being such that 75 when both circuits formed thereby are closed said core is inoperatively energized.

ODILON BRISBOIS.

In the presence of—

CHARLES TURNER BROWN,
CHARLES B. HEBRON.
